UNITED STATES PATENT OFFICE.

ANDREW R. RIDDERSTROM, OF NAHANT, MASSACHUSETTS, ASSIGNOR, BY MESNE ASSIGNMENTS, TO THOMAS C. ROWEN, OF SWAMPSCOTT, MASSACHUSETTS.

CHANNEL-LIP-TURNING MACHINE.

Application filed February 26, 1920. Serial No. 361,532.

To all whom it may concern:

Be it known that I, ANDREW ROBERT RIDDERSTROM, a citizen of the United States, and resident of Nahant, in the county of

5 Essex and State of Massachusetts, have invented a new and useful Improvement in Channel-Lip-Turning Machines, of which the following is a specification.

The present invention relates to channel-10 lip-turning machines, and more particularly to machines for turning back the channel lips of stiffened soles.

Owing to the great strain to which the channel lip is subjected during the operation 15 of opening and turning it and pressing it flat, the sole must be gripped firmly by the feeding instrumentalities to prevent the sole being pushed bodily away and out of the machine. As a metal stiffener of a stiffened sole is naturally of harder and less yielding quality than the body of the sole, the firm gripping action causes it to bind 20 in the machine, thereby either clogging up and completely stopping the operation of the machine, or else injuring the sole or even 25 the machine parts. It has accordingly been customary hitherto to turn back the channel lip before attaching the stiffener to the sole.

30 An object of the present invention is to provide an improved machine particularly adapted for operation upon stiffened soles.

The combined firm gripping and feeding action is customarily effected by a feed 35 wheel that is spring-pressed towards the wiper with great force. In order that the sole may be initially introduced between the feed wheel and the wiper, the feed wheel must be bodily treadle-actuated, in 40 opposition to the action of the spring, away from the wiper. The treadle is then released to permit the spring to return the feed wheel towards the wiper and thus grip the sole.

45 The construction is such that an appreciable time interval must elapse before the feed wheel is returned by the spring to its normal position. As the feed wheel can not bite deeply into the sole until after the

lapse of the time interval, it has a tendency, 50 especially when operating at a high speed, to dig a groove into the leather and thereby damage the sole.

It is accordingly another object of the present invention to eliminate this damaging 55 tendency of the feed wheel.

To this end, a feature of the invention resides in slowing down the feed wheel when it initially engages the sole, permitting it to secure a firmer grip before it commences 60 to feed the sole at full speed. Another feature contemplates the provision of a quick-acting torsion spring having large leverage, whereby the machine is made to respond more quickly to the release of the treadle, 65 and whereby the above-mentioned time interval becomes greatly reduced.

Still another object of the invention is to improve upon machines of the above-described character, so as to adapt them 70 for operation at high speed.

With the above objects in view, the invention consists of the improved machine hereinafter described, illustrated in the accompanying drawings and defined in the 75 appended claims.

In the drawings, Fig. 1 is an elevation of a machine embodying the invention in its preferred form; Fig. 2 is a front-end elevation thereof; Fig. 3 is an enlarged view, 80 partly in section, showing the machine in the act of turning and pressing down a channel lip; Fig. 4 is a perspective view of a shank-stiffened outsole; Fig. 5 is a detail view showing a preferred yielding connection between the feed wheel and its driving mechanism; Fig. 6 is a rear elevation of a preferred feed wheel; and Fig. 7 is a sectional view, taken upon the line 7-7 of Fig. 1, looking in the direction of the arrows.

85 The invention is conveniently illustrated in its preferred form in connection with a machine of the general type disclosed in a patent to Stanbon, No. 607,139, granted July 12, 1898, to which patent reference may be had for a clearer understanding of so much of the machine illustrated in the ac-

companying drawings as is not fully explained herein because unnecessary to an understanding of the present invention. The machine embodies a horizontally rotatable 5 wiper 2 that is adapted to open, turn over and press flat a channel lip 4 of a previously channeled outsole 6, as shown more particularly in Fig. 3. As the lip 4 is subjected to considerable strain during this 10 operation, the sole must be firmly gripped to prevent its being pushed outwardly away from the machine. The desired firm gripping action is effected by a toothed feed wheel 8 on one side of the sole and the 15 wiper and a presser foot 10 upon the other. As the sole is advanced by the feed wheel to the wiper, it is guided by an adjustable guide 12 which lies in the sole channel and bears against the shoulder of the lip, and 20 it is gauged by an adjustable gauge 14 in a manner more fully described in the above-mentioned patent.

The present invention is concerned more particularly with machines for operating 25 upon stiffened soles. For the sake of concreteness, a molded, shank-stiffened outsole is illustrated in Fig. 4, the shank stiffener 16 of which extends from the heel to near the ball of the sole. The shank may be applied to the inner face 18 of the sole in any 30 desired manner, as by securing it to the sole at one end 20, as shown, or at both ends. As the shank stiffener is usually of steel or other metal, a material that is much harder 35 than the body of the sole, there is a tendency, owing to the above-described firm gripping action of the feeding instrumentalities, for the sole to wedge in between the elements of the feeding mechanism, resulting either 40 in stopping the operation of the machine or in injuring the outsole or the machine parts.

According to the present invention, therefore, the shank 16 is not gripped so firmly, if at all, as are other portions of the sole. 45 In the specific embodiment of the invention that is herein illustrated and described, provision is made for gripping the shank 16 yieldingly, though firmly gripping other portions of the sole. In the illustrated embodiment of the invention, this result is attained by mounting concentrically with the feed wheel 8, and adjacent thereto, in side-by-side relation, a second feed wheel 22 of smaller diameter that is adapted to yield 50 upon pressure being applied to its periphery, as when pressed inwardly by the shank 16. The specific mechanism for effecting this end will now be described. The feed wheel 8 is provided with a centrally positioned opening 24 (Fig. 3) through which is adapted to enter a boss 26 that is integral with a gear 28 that is rotatably mounted upon an inclined stud 30. The feed wheel 22 is also provided with a centrally positioned opening of greater diameter than

that of the boss 26, indicated at 32, whereby it may be loosely mounted upon the boss 26. The feed wheel 8 is thus, in effect, provided with a centrally positioned boss which extends into the opening 32 of the feed wheel 70 22. The feed wheels are secured against lateral movement along the boss by a securing plate 34. The feed wheel 22 is further provided with radial recesses 36 (Fig. 6) having reduced apertures 38 communicating with 75 the central opening 32. Plungers 40 are mounted in the apertures and are spring pressed into the central opening 32 to engage the boss 26 by springs 42 in the radial recesses. The feed wheel 22 is thus laterally 80 yieldably mounted upon the feed wheel 8, but is normally, when the machine is not in operation, yieldingly maintained in central position thereon. The feed wheels are adapted to be rotated as a unit by the gear 85 28 about the stud 30 by connecting them together as shown more particularly in Figs. 5 and 6, the feed wheel 22 being provided with a pin 44 that enters a slot 46 in the feed wheel 8. The slot 46 is of larger diameter than the diameter of the pin 44 so as to permit the above-described yielding lateral movement of the feed wheel 22 upon the feed wheel 8.

In operation, the feed wheel 22 yieldingly 90 grips the stiffener shank 16 along the edge, the feed wheel 8 firmly grips an adjacent edge portion of the face 18 of the sole, the wiper 2 and the presser foot 10 at the same time firmly gripping the other face of the sole at points opposed to the feed wheels. In case too great a strain is placed upon the sole, the shank 16 presses in upon the periphery of the feed wheel 22, causing its 95 surface to yield while the grip upon the sole 100 is still maintained. Very satisfactory operation is thus obtained.

The feed wheel 22 is preferably of slightly smaller diameter than the feed wheel 8 so as to accommodate the extra thickness of 105 the shank 16, as shown in Fig. 3. To provide for a larger bearing surface, the periphery of the feed wheel 22 may safely be made of greater width than the width of the feed wheel 8. This end is facilitated by 110 conically inclining the peripheral surface of the feed wheel 22, rendering it horizontal at its uppermost position, as shown at 48, to compensate for the inclination of the stud 30.

The wings of the wiper 2 incline upwardly 120 away from the wiper-carrying shaft, as shown, so as to cooperate at a suitable angle with the inclined feed wheel 22.

The feed wheel 22 may be of varying thickness, dependent upon the dimensions 125 of the shank of the sole, and its position upon the machine should always be such that the force exerted by the upwardly inclining wings of the wiper, in pressing back the channel lip, shall lie along a line L, Fig. 130

3, parallel to the feed wheel and approximately midway between its faces. The consequent positioning of the feed wheel 8 is such that the end of the guide 12 lies substantially in the plane parallel to the faces of the feed wheel 8 and approximately midway between them. The upper, gripping portion of the periphery of the feed wheel lies between the wiper wing and the gauge 14, preferably a little to one side of the end of the guide 12, toward the gauge. It therefore becomes necessary to vary the position of the feed wheel 8 relatively to the wiper, the presser foot and the guide, depending upon the size and the position of the feed wheel 22. A preferred construction for effecting the desired adjustment of the feed wheels will now be described.

The stud 30 upon which the feed wheels 20 are mounted, a pinion 50 (Fig. 2) that drives the gear 28, a shaft 52 (Fig. 1) to one end of which the pinion is fixed, and bearings 54 for the shaft are all carried upon a frame or carrier 56. Adjustment of the carrier 56 will thus result in adjustment of the feed wheels and their driving mechanism. The carrier 56 is provided with an opening 58 (Fig. 7) adapted to receive the eccentric pin 60 of an eccentric post the concentric portion 62 of which is journaled in the frame or support 64 of the machine. Rotative adjustment of the eccentric post will thus result in adjusting longitudinally the carrier 56 and the feed wheels carried thereby. The feed wheels may thus be adjusted laterally, to the right or to the left (Figs. 1 and 3) of the wiper wings, as desired. The eccentric post may be rotatably adjusted by means of a handle 66, and the carrier 56 may be clamped thereto by a screw 68.

Not only is provision made by this construction for the above-described adjustment, but the carrier becomes thus adapted for pivotal movement upon the machine about the concentric portion 62 of the eccentric post. The free end of the carrier is spring-pressed upwardly, so as to maintain the feed wheels in operative position relatively to the wiper. The feed wheels may be separated from the wiper, to permit the introduction of a sole, by a treadle 70 acting, in opposition to the force of the spring, to move the free end of the carrier 56 downwardly about the concentric portion 62 of the eccentric post as a pivot. Upon the treadle being released, the spring effects a return of the carrier to its normal position. The design of the machine of the above-referred to patent is such that the sluggish spring there disclosed does not operate sufficiently rapidly to meet modern, high-speed demands. The consequence is that the teeth of the rapidly rotating feed wheel have a tendency to bite suddenly, but not deeply, into the sole and, through their high-speed, rotative movement, cut a groove therein, damaging the sole. To overcome the effects of this damaging tendency, provision is made, according to the present invention, for preventing the feed wheel initially acting upon the sole with its full force. The machine is thus adapted to operate at high speed, but without in any way injuring the leather of the sole.

The rotative movement of the driving mechanism is initially not fully transmitted to the feed wheel, its speed becoming thus temporarily slowed down at the moment when it engages the sole, affording it an opportunity to bite deeply into the sole leather before the feeding is resumed at high speed. In the specific embodiment which is herein illustrated and described, the desired result is attained by so connecting the feed wheels 85 to their driving mechanism as to permit a backward yielding rotative movement of the feed wheels relatively to the driving mechanism. The gear 28 is internally grooved at 84 to receive compression springs 86 the ends of which are confined between posts 88 and 90 that are respectively secured to the gear 28 and the feed wheel 8. When a sole is first introduced into the machine, therefore, and the treadle is released, the feed wheels are spring-actuated into engagement with a portion of the sole near the edge and with the shank 16. As the leather is firm enough to overcome the tendency of the springs 84 to keep the feed 100 wheels in the position indicated in Fig. 5, this engagement of the feed wheels by the sole effects a retarding action which causes the feed wheels to slow down or yield backwardly relatively to the gear 28 of the driving mechanism. The feed wheels are thus forced to assume their normal feeding position, illustrated in Fig. 3, with the springs 84 under tension, and not until they assume this position do they become fully 110 effective to advance the sole at full speed. The sole is, however, advanced, at a slower speed. While the feed wheels are thus slowing down, the feed wheel 8 is afforded an opportunity to bite deeply into the leather 115 and obtain a firm grip thereon, the feed wheel 22 at the same time yieldingly gripping the shank 16, and the presser foot and the wiper firmly gripping the other face of the sole at points opposed to the gripping 120 points of the feed wheels.

The attainment of the desired result may further be aided by causing the feed wheel to respond more quickly to its actuating spring, so that it may bite deeply into the sole immediately upon the release of the treadle. In this manner, the damaging grooving tendency existant when the feed wheel suddenly engages a surface layer only of the leather becomes eliminated. Accord-

ing to the present invention, the free end of the carrier is maintained in its normal position by the free end of a torsion spring 72 that is wound about a drum 74 that is secured to a point of the machine frame 64 that is far removed from the feed wheels, so as to provide for large leverage. The force of the spring may be adjusted by a handle 76 that is adapted to rotatably adjust the drum, and the drum be locked in adjusted position by a spring pressed plunger 78 acting as a pawl to engage the teeth of a ratchet wheel 80. The plunger 78 may be moved upwardly, in opposition to the force of its spring, so as to release the drum, by a handle 82. It has been found that a spring of this character, with large leverage to render it quick-acting, when suitably adjusted, renders the feed wheels very actively responsive to the release of the treadle. The spring serves an additional function in quickly returning the feed wheels to operative position when temporarily displaced therefrom by irregularities in the sole, such as those at the junction between the ball and the shank of a molded sole, thus contributing to the efficiency of high-speed machines.

The shaft 52 is driven from a gear 92 (Fig. 1) affixed thereto and meshing with a worm 94, as in the above-referred to patent. It has been found that the corresponding worm and gear of the patented machine wore down very quickly when operated at high speed, rendering the machine practically useless, so that for this reason, among others, the machine fell into disfavor. The worm 94 of the present machine has accordingly been considerably reduced in diameter so that it may operate at a smaller peripheral speed, and the number of its threads has been increased. The gear 92 has been correspondingly increased in diameter so as to maintain the balance. The provision of the comparatively small worm 94 and the correspondingly large gear 92 results in the reduction of the friction between them to a minimum, rendering their operation at high speed very satisfactory. The worm 94 is driven through bevel gears 96 and 98 from a pulley 100 which, through bevel gears 102 and 104, drives also the vertical shaft upon the lower end of which the wiper 2 is mounted. The feed wheels and the wiper are thus continually operated from the same source.

Although the invention has been illustrated in connection with a machine for turning the channel lips of stiffened soles, it will be obvious that certain features thereof are not so restricted, but are applicable to machines for turning the channel lips of any type of sole. Some features of the invention, indeed, are of more general applicability than to channel-lip-turning

machines. It will be understood, therefore, that the invention is not limited to the exact embodiment thereof that is herein illustrated and described, but is subject to modification, the scope of the invention being indicated by the appended claims. 70

What is claimed as new is:

1. A channel-lip-turning machine having, in combination, a frame, a shaft vertically mounted in the frame, a wiper carried by the lower end of the shaft so as to be horizontally rotatable, the wiper being provided with a wing inclining upwardly away from the shaft adapted to turn the channel lip of a shank-stiffened, channeled sole, and means for feeding a shank-stiffened, channeled sole to the wiper comprising a feed wheel mounted at an incline to the vertical having a section positioned so that the upper portion of the section is adapted to grip firmly a portion of the sole adjacent to the shank stiffener along the edge of the sole, the feed wheel having a section of smaller diameter than the first-named section. 75 80

2. A feed mechanism having, in combination, a stud, two feed wheels rotatable thereon, one of the feed wheels being yieldably mounted upon the stud, and a presser foot for cooperating with the feed wheels. 90

3. A feed mechanism having, in combination, a feed wheel having a centrally positioned boss, a feed wheel having a central opening of greater diameter than that of the boss, whereby it may be mounted upon the boss, and radial recesses, and plungers 100 mounted in the recesses and spring-pressed into the opening, the boss extending into the opening and being engaged by the spring-pressed plungers, whereby the second-named feed wheel is laterally yieldably maintained 105 upon the first-named feed wheel. 95

4. A feed mechanism having, in combination, a feed wheel having a centrally positioned boss rotatably mounted upon a stud, a feed wheel having a central opening of 110 diameter greater than that of the boss, whereby it may be mounted upon the boss, and radial recesses, spring-pressed plungers mounted in the recesses and extending into the opening to engage the boss, whereby the second-named feed wheel is laterally yieldably mounted upon the first-named feed wheel, and means whereby the feed wheels may be rotated about said stud as a unit. 115

5. A feed mechanism having, in combination, a carrier, a feed wheel carried thereby, a support, means for adjusting the carrier upon the support to adjust the position of the feed wheel, means for securing the carrier in adjusted position, and means carried 125 by the carrier for operating the feed wheel.

6. A feed mechanism having, in combination, a support, a carrier mounted thereon, a feed wheel carried by the carrier, a gear carried by the carrier for rotating the feed 130

wheel, a gear mounted upon the support meshing with the first-named gear, means for rotating the second-named gear, and an eccentric for adjusting the carrier upon the 5 support to adjust the position of the feed wheel, said gears being adapted to move relatively to each other without disengaging during the adjustment.

7. A channel-lip-turning machine having, 10 in combination, a support, a wiper, a carrier, two inclined feed wheels for advancing a sole to the wiper mounted upon the carrier, said wheels being mounted in side-by-side relation, one of the wheels being adapted to grip the shank and the other wheel an adjacent portion of a shank-stiffened sole and an eccentric post journaled in the frame for adjusting the carrier and about which the carrier is pivotally mounted upon the 20 support.

8. A channel-lip-turning machine having, in combination, a frame, a vertical shaft, a wiper carried by the lower end of the shaft so as to be horizontally rotatable, the wiper 25 being provided with a wing inclining upwardly away from the shaft adapted to turn the channel lip of a shank-stiffened, channeled sole, and two adjacently disposed, concentrically mounted feed wheels of different 30 diameter for advancing the sole to the wiper mounted at an incline to the frame with the upper portion of the periphery of the larger feed wheel positioned between the wiper wing and the frame, the smaller feed wheel 35 being adapted to grip yieldingly the shank stiffener and the larger feed wheel being adapted to grip firmly a portion of the sole adjacent to the shank stiffener along the edge of the sole.

40 9. A channel-lip-turning machine having, in combination, a wiper, a feed wheel for advancing a channeled sole thereto, a shaft for driving the feed wheel, and means for longitudinally adjusting the shaft to adjust 45 the position of the feed wheel laterally of the wiper.

10. A machine for turning the channel lip of a sole that is stiffened with a shank stiffener applied to one face thereof having, in 50 combination, a wiper, and means for feeding the sole to the wiper, said means comprising two adjacently disposed, feed wheels of different diameter one of which is normally, when the machine is not operating, 55 yieldingly positioned concentrically of the other and adapted to yieldingly grip the shank, and the other being adapted to firmly grip said face of the sole at a portion adjacent to the shank, and means cooperating 60 with the feed wheels to firmly grip the other face of the sole.

11. A channel-lip-turning machine having, in combination, a wiper, a spring-pressed feed wheel for advancing a channeled sole thereto, means for actuating the 65

feed wheel in opposition to its spring preparatory to the introduction of the sole between the feed wheel and the wiper, and means for temporarily slowing down the speed of the feed wheel following the release of the actuating means to permit the feed wheel to bite deeply into the sole preparatory to the feeding movement at normal speed.

12. A channel-lip-turning machine having, 70 in combination, a wiper, a feed wheel, means for rotating the feed wheel to advance a channeled sole to the wiper, and means whereby the rotating means becomes initially not fully effective, thereby to prevent the feed wheel damaging the sole.

13. A channel-lip-turning machine having, 75 in combination, a wiper, a feed wheel for advancing a channeled sole to the wiper, means for rotating the feed wheel, and means whereby the rotative movement of the rotating means is initially not fully transmitted to the feed wheel, thereby to prevent the feed wheel damaging the sole.

14. A channel-lip-turning machine having, 80 in combination, a wiper, a feed wheel for advancing a channeled sole thereto, a quick-acting spring for actuating the feed wheel toward the wiper, driving means, and means connecting the feed wheel to the driving means so as to permit a yielding backward rotative movement of the feed wheel relatively to the driving means.

15. A channel-lip-turning machine having, 85 in combination, a frame, a wiper and a feed wheel for advancing a channeled sole to the wiper mounted upon the frame, a quick-acting torsion spring secured to a point of the frame far removed from the feed wheel so as to have a large leverage, the free end of the spring acting upon the feed wheel to actuate it towards the wiper, and manually operable means for actuating the feed wheel in opposition to the force of the spring preparatory to the introduction 90 of the sole between the feed wheel and the wiper.

16. A channel-lip-turning machine having, 100 in combination, a frame, a shaft vertically mounted in the frame, a wiper carried by the lower end of the shaft so as to be horizontally rotatable, the wiper being provided with a wing inclining upwardly away from the shaft adapted to turn the channel lip of a shank-stiffened, channeled sole, and means for feeding a shank-stiffened, channeled sole to the wiper comprising a feed wheel mounted at an incline to the vertical having a section positioned so that the upper portion of the section is adapted to grip firmly a portion of the sole adjacent to the shank stiffener along the edge of the sole, the feed wheel having a section of smaller diameter than the first-named section, and the periphery of the second- 105

110

115

120

125

130

named section being cone shaped with the walls of the cone converging away from the first-named section.

17. A channel-lip-turning machine having, in combination, a wiper for turning the channel lip of a shank-stiffened, channeled sole, and a feed wheel for advancing the sole to the wiper comprising two adjacently disposed sections of different diameter, the larger section being adapted to grip firmly a portion of the sole adjacent

to the shank stiffener along the edge of the sole, and the smaller section being adapted to be engaged by the shank stiffener.

18. A channel-lip-turning machine as defined in claim 17 in which the wiper is horizontally rotatable and the feed wheel is inclined to the vertical.

In testimony whereof, I have hereunto subscribed my name this 24th day of Feb- 20
ruary 1920.

ANDREW R. RIDDERSTROM.
